DOOR OPERATING MECHANISM FOR LOAD
DISCHARGING CARS

Albert E. Zimmer, Chicago, Ill., assignor to Enterprise Railway Equipment Company, Chicago, Ill., a corporation of Illinois

Application March 21, 1946, Serial No. 655,906

6 Claims. (Cl. 105—300)

1

This invention relates to improvements in door operating mechanism for load-discharging gondola cars.

One object of the invention is to provide in connection with operating mechanism for doors of load-discharging cars, including rotary winding means for lifting the doors to closed position, means for protecting the attendant against injury by moving parts of the winding means.

A more specific object of the invention is to provide in load-discharging gondola cars having door operating mechanism including a rotary winding means of a type which, while being rotated to open the doors, travels outwardly toward the side of the car and beyond the side wall thereof, a shielding hood which covers the exposed parts of the rotary winding means and travels with said means at all times to provide protection for the attendant while at the side of the car and more particularly when he is standing or holding on to the side ladder of the same.

Other objects of the invention will more clearly appear from the description and claims hereinafter following.

In the drawings, forming a part of this specification, Fig. 1 is a side elevational view of one end portion of a load-discharging gondola car, illustrating my improvements in connection therewith. Fig. 2 is a transverse, vertical sectional view, corresponding substantially to the line 2—2 of Fig. 1, showing the structure at one side of the longitudinal center of the car, with the doors in fully closed position, the open position of the same being indicated in dotted lines. Fig. 3 is a horizontal sectional view, corresponding substantially to the line 3—3 of Fig. 1. Fig. 4 is a view similar to Fig. 2, on an enlarged scale and partly broken away, showing the position of the parts when the door is completely open.

In said drawings, my improvements are illustrated in connection with a well-known type of operating mechanism for doors of load-discharging gondola cars, having the doors arranged in two rows lengthwise of the car at opposite sides thereof and hinged along their inner edges to the center sill structure to swing downwardly to discharge the load, and wherein the operating mechanism for the doors comprises lengthwise extending, manually actuated, rotatable shafts at opposite sides of the car adjacent to the outer edges of the doors, for winding flexible connections by which the doors are lifted, the shafts being bodily displaceable laterally inwardly beneath the doors to effect locking of the latter in closed position.

2

Referring to the drawings, which illustrate the structure at one end of such a car, 10 indicates a portion of the side wall of the car at said end, and 11 the lower chord member of said side wall. 5 The side ladder, which is located at this end of the car, comprises the usual vertically extending side rails 12—12, which are fixed to the side wall 10, having rungs 13 fixed at opposite ends to the side rails, and a depending stirrup 14 hung from the bottom of the car, the bottom cross piece of the stirrup providing the bottom step 15 of the ladder. The stirrup is also provided with a cross bar or rung 16 above said step 15, forming the second step of the ladder. As illustrated in the drawing which shows only one side of the end of the car and one door 17, this door is hinged along its inner edge on brackets 18 fixed to the center sill structure 19 of said car, and is swingable to the dotted line position shown in Fig. 20 when dropped open. As will be understood, all 15 of the doors of the car are mounted in a similar manner. The usual rotary winding shaft 20 is disposed lengthwise of the car, being supported adjacent to the outer edges of the doors at the corresponding side of said car by the bracket 21 and similar brackets arranged at spaced intervals lengthwise of the car. The guide bracket 21, as shown in Fig. 4, is secured to the vertical web 22 of the body bolster 23 of the car and is provided with the usual horizontal guide slot 121, which accommodates the shaft 20 for lateral displacement, the outer end portion of said slot being downwardly offset, as shown, to maintain the shaft in its initial winding position in operating the doors. As is well understood in this art, the shaft 20 moves laterally inwardly after the operating means has lifted the doors to closed position, to lock the latter tightly closed. The door 25 20 is lifted from the dotted line position shown in Fig. 2 to the closed position shown in full lines by the usual link connection 24, comprising links 26, 27, and 28, which are wound on a hub member 29 fixed to the shaft 20, the link 25 at the inner end of the connection being pivotally connected to a projecting arm 30 on said hub, and the link 28 at the other end of the same being pivotally connected to a projecting bracket 31 at the outer edge of the door 17.

In load-discharging cars having door operating mechanisms of this character, the arrangement is such that the winding mechanisms for operating the doors at opposite sides of the car at each end thereof are placed where they might cause injury to a person standing on or holding 30 to side ladders or grab irons. In other words,

when the shaft 20, which carries the hub 29, is in the outermost position, as shown in Fig. 4, the hub and the connection 24 being wound thereon protrude some distance beyond the side of the car between the side rails of the ladder and may cause injury to a person standing on or holding onto the ladder.

In carrying out my invention, I provide broadly a shielding hood A for the winding means of the door operating mechanism, and a guard wall B mounted on the side of the car immediately beneath the side wall thereof and in alignment therewith and having an opening therein to accommodate the hood.

The hood A, which is preferably made of sheet metal, has spaced side walls 32-32, a bottom wall 33, a vertical front wall 34, and a curved top wall 35. The top, front, and bottom walls extend from one side wall to the other and are preferably formed integral therewith. The hood is thus open at the back.

As clearly shown in Fig. 1, the middle portions of the side walls 32-32 extend vertically and are substantially parallel to each other, and the upper and lower portions of said walls above and below said parallel portions are inclined laterally inwardly, that is, the upper portions are inclined inwardly toward each other in upward direction and the lower portions are inclined inwardly toward each other in downward direction. The hood A thus presents a transverse, vertical section of substantially octagonal shape. These side walls also converge toward each other very slightly toward the front of the hood, as shown in Fig. 3. Adjacent to the front wall 34, the bottom wall 33 is depressed or bulged downwardly, as indicated at 36, to properly support the hood when in the position shown in Fig. 2, as herein-after pointed out. The side walls 32-32 are spaced so as to embrace the hub 29 of the winding means, and the links wound thereon at opposite sides. These side walls are provided with aligned circular openings 37-37, which accommodate the rotary shaft 20. The openings 37-37 are of slightly greater diameter than the shaft so that the shaft is freely rotatable therein and still fits the openings to effect movement of the hood bodily therewith in lateral direction when the shaft is laterally displaced in the guideway 121 of the guide bracket 21. The top, bottom, and front walls 35, 34, and 33, are spaced such a distance from the center of rotation of the shaft 20 that ample clearance is provided for the connection 24 being wound on the hub 29, the curvature of the top wall 35 being on an arc having the same center as the shaft 20. A lengthwise extending, laterally projecting, horizontal guide flange 38 is provided on the hood A at the left-hand side thereof, as seen in Figs. 1 and 3, said flange being located on the vertical section of the corresponding side wall 32 and projecting laterally therefrom.

The guard wall B is provided by the usual sub-side sill of the car immediately beneath the side wall 10 in back of the ladder and extends beyond the opposite sides of the latter, as clearly shown in Fig. 1. The main body portion of this wall is in a vertical plane aligned with the side wall 10 of the car. At its upper end, the wall B is secured to the horizontal section of the lower chord member 11 of the side wall of the car, being provided with an inturned flange 39 secured by rivets, as shown in Fig. 2. As shown most clearly in Figs. 2 and 4, the wall B is provided with the usual inturned horizontal flange 41 at

its lower end which underlies the bottom wall of the hood A, and an inclined section 42 immediately above the flange 41. The flange 41 is preferably cut away on its inner side, as indicated at 43, to provide clearance for the flexible connection 24 as it is being unwound from the hub of the shaft 20.

As shown in Fig. 1, the wall B has an opening 44 therethrough corresponding in shape to the transverse vertical shape of the hood, but slightly larger than the hood to provide clearance for the necessary upward and downward displacement of the hood jointly with the shaft 20 as the shaft is operated to close and open the door. At the left-hand side of the opening 44, the wall B has a guide slot 45 therethrough, which communicates with said opening and is adapted to accommodate the guide flange 38 of the hood A. This slot is of a size to provide ample clearance for the guide flange 38 during the upward and downward displacement of the hood hereinbefore referred to.

When the door 17 is in closed position, as shown in Fig. 2, the actuating shaft 20 of the door operating mechanism is at the extreme right-hand end of the slot 121 of the bracket 21, with the chain 24 wound on the drum, locking the door in closed position. In this position of the parts, the front or outer side of the hood A is just to the rear of the wall B and the depressed portion 36 of the bottom wall 33 rests on the bottom wall of the opening 44, thus blocking the opening and effectively preventing a person on the side ladder from accidentally getting his foot, or hand, or any other portion of his body in the opening of the wall. In this position of the hood A, the guide flange 38 thereof projects into the slot 45 of the wall B to prevent rotation of the hood with the shaft 20.

To open the door 17, the shaft 20 is rotated in clockwise direction, as viewed in Fig. 2, thereby unwinding the links 24 from the hub 29 of the shaft, forcing the shaft to slide from beneath the door toward the outer end of the slot 121 to unlock the door, bringing the shaft to approximately the position shown in Fig. 4. In this position, the shaft 20 has dropped into the depressed front end portion of the slot 121. As will be evident, the hood A is carried outwardly by the shaft to the position shown in Fig. 4, the bottom wall of the hood riding on the bottom wall of the opening 44 of the wall B, thereby lowering the hood to correspond with the dropping of the shaft 20 as it enters the depressed portion of the slot 121; this movement of the hood being permitted by the higher level portion of the wall 33 to the rear of the bulge 36. During this outward displacement of the hood together with the shaft 20, rotation of the hood about the axis of the shaft is effectively prevented by the bottom wall of the hood being guided on the bottom wall of the opening 44 and by engagement of the guide flange 38 within the slot 45 of the wall B. Inasmuch as the door 17 is free to drop after it has been unlocked, the weight of the same exerts a strong pull on the links 24, tending to unwind the same and causing the shaft 20 and the winding mechanism to spin at high speed. During this action, the shielding hood A fully protects any one standing on or holding onto the ladder from injury, which might otherwise occur due to the projecting position of the rapidly rotating winding means.

During the operation of closing the doors or lifting the same to closed position by rotation

of the winding means, the shaft 20 is rotated in contraclockwise direction, that is, it is rotated in a direction reverse to the rotation thereof in opening the doors, and the operation of all of the parts is substantially the reverse of that described in connection with the door-opening operation, movement of the shaft 20 and the hood A being in a direction inwardly of the car, the hood A covers the exposed parts of the wind-hood receding through the opening of the wall B 10 to the position shown in Fig. 1. Inasmuch as ing means and blocks the opening of the wall B in all possible positions of the operating mechanism in opening and closing of the doors, full protection against injury is provided for any person standing on or holding onto the ladder.

I claim:

1. In a door operating mechanism for load-discharging cars, the combination with a rotary actuating shaft; of winding means on said shaft, said shaft together with the winding means being laterally displaceable during operation thereof; a hood overhanging said winding means, said hood being connected to said shaft for displacement in unison therewith; and means for holding said hood against rotation with respect to said shaft.

2. In a door operating mechanism for load-discharging cars having a vertical side wall, the combination with a rotary actuating shaft parallel to said side wall; of winding means on said shaft, said shaft together with said winding means being laterally displaceable toward and away from said wall during operation thereof; a hood covering said winding means, said hood being connected with said shaft for bodily displacement therewith; a vertical guard wall beneath said side wall in alignment therewith, said guard wall having an opening therethrough to accommodate said hood; and cooperating guide means on said hood and guard wall for holding the hood against rotation with the shaft.

3. In a door operating mechanism for load-discharging cars, the combination with a rotary actuating shaft parallel to the side of the car; of winding means on said shaft, said shaft together with the winding means being laterally displaceable toward the side of the car during operation of said shaft, said winding means being projected outwardly beyond the side of the car during said lateral displacement thereof; a hood overhanging and covering said winding means at the outer side thereof, said hood being connected to the shaft for lateral displacement in unison therewith; a guard wall at the side of the car, said wall having an opening therethrough to movably accommodate said hood; and cooperating guide means on said wall and hood for holding the hood against rotation with the shaft.

4. In a load-discharging drop-door car having a vertical side wall and a side ladder on said wall, the combination with a rotary winding means for

opening and closing the doors of said car; of a rotary shaft for actuating said winding means, said shaft being parallel to said side wall and having the winding means mounted thereon for rotation therewith, said shaft together with said winding means being laterally displaceable toward said wall and beyond the same during operation thereof; a hood covering said winding means at the top, bottom, sides, and front thereof, said hood being connected to said shaft for bodily displacement therewith; a vertical guard wall beneath said side wall in alignment therewith, said guard wall having an opening therethrough to accommodate said hood; and cooperating guide means on said hood and guard wall holding said hood against rotation with the shaft.

5. In a load-discharging drop-door car having a vertical side wall and a side ladder on said wall, the combination with a rotary winding means for 20 opening and closing the doors of said car; of a rotary shaft for actuating said winding means, said shaft being parallel to said side wall and having the winding means mounted thereon for rotation therewith, said shaft together with said winding means being laterally displaceable toward said wall and beyond the same during operation thereof; a hood covering said winding means, said hood being connected to said shaft for bodily displacement therewith; a vertical 25 guard wall beneath said side wall in alignment therewith, said guard wall having an opening therethrough between the sides of the ladder to accommodate said hood; and cooperating guide means on said hood and guard wall holding said hood against rotation with the shaft.

6. In a door operating mechanism for load-discharging cars, the combination with a rotary 40 shaft and winding means on said shaft rotatable therewith, said shaft being disposed lengthwise of the car and being laterally displaceable during operation thereof; of a hood covering said winding means, said hood having spaced side 45 walls embracing said winding means on opposite sides, said walls having aligned openings therethrough rotatably accommodating said shaft; a guideway on the car; and a guide flange on said hood slidingly engaged in said guideway for holding the hood against rotation with the shaft.
